UNITED STATES PATENT OFFICE

GEORGE E. MCINTYRE, OF KANSAS CITY, MISSOURI

CARD HOLDER

Application filed November 22, 1930. Serial No. 497,443.

This invention relates to a new article of manufacture formed of metal or other suitable material to produce a card holder especially adapted for attachment to the instrument board of an automobile, and the primary object of the invention is to provide a card holder that is cheap to manufacture, readily attachable in the operative position and embodies structural refinements which renders the same efficient and highly desirable as an inexpensive commodity which may be used as an advertising feature.

One of the objects of the invention is the provision of a card holder having in combination with the ordinary easel member thereof, a novelly constructed supporting bracket which includes clamping means to allow the placement of the article upon the support.

Minor objects and details of construction will appear during the course of the following specification, referring to the accompanying drawing, wherein

Figure 1 is a perspective view of a card holder made in accordance with this invention.

Fig. 2 is a vertical central section through the card holder.

Fig. 3 is a side elevation of the same.

Fig. 4 is a side elevation of the holder showing the clamping means, and

Fig. 5 is a perspective view of a card holder embodying a modified form of construction.

Like reference characters are used to designate similar parts throughout the several views and the numeral 6 indicates an easel portion of a card holder utilized to support a card or sheet of paper, upon which may be written any desired data which the user wishes to keep before him. Easel 6 is provided with inturned flanges 8 formed along the vertical opposite sides of easel 6 and overlapping the transparent sheet of celluloid or similar material 10 which may be also supported by easel 6 in front of the card or paper 12.

In forming this card holder, it is preferable to use material which allows bending into the proper shape and which is suscep-

tible of a slight amount of spring action so that the support which is to carry the card holder may be moved between the back of easel 6 and a wall 14 which is positioned as illustrated by rebending the material rearwardly of the easel 6 and in spaced relation thereto. The supporting bracket proper of this card holder might be said to extend from the bottom of easel 6 to the upper end of wall 14. To perform one of the important functions of the invention, a convexo-concave stop 16 is formed along the juncture of said easel 6 and the supporting bracket; said stop actually forming a portion of the supporting bracket of the card holder.

Card 12 is held by easel 6 so that the action of gravity causes it to rest against the convex portion of stop 16. The concave portion of this stop 16 might be engaged by a portion of a support 18 which projects beneath easel 6.

In this instance, support 18 is an instrument board of an ordinary automobile formed to present a bead 20 along the lower edge thereof. In some instances this bead 20 will conform to the concavity of stop 16, while other instrument boards will present a square corner and no part thereof will project beneath easel 6. Manifestly, the card holder may be attached to either style of instrument board or support 18 without altering the card holder in any way.

This invention contemplates the use of a simply constructed clamping means which is carried by the bracket behind easel 6. Figs. 1 to 4 inclusive illustrate one embodiment of this feature and includes a lug 22 which is struck from wall 14 and the connecting portion 24 of the supporting bracket portion of the card holder.

As illustrated, lug 22 is preferably disposed substantially parallel to wall 14 and is connected thereto by a foot portion 26 which serves the purpose of holding lug 22 in spaced relation with wall 14, as well as to engage one side of a nut 28 to preclude its turning. Nut 28 rests between lug 22 and wall 14, and the tapped opening therethrough registers with holes 30 and 32 formed through wall 14 and lug 22 respectively, all of which permits the passage of a bolt 34, which is threaded to

coact with the tapped opening in nut 28 and which is formed to present a head 36 utilized in adjusting the clamping means.

The parts just described form the clamping means assembly which is behind easel 6. Obviously, bolt 34 may be moved to engage the instrument board support 18 to secure the card holder in place.

Modifications might be followed in forming a card holder having the points of invention just above set forth and such a modification has been illustrated in Fig. 5. Parts common to both forms illustrated are numbered alike herein and but few points of difference are present. In the modified form a stop 50 is pressed outwardly from easel 6 on a line connecting the bottoms of inturned flanges 8. This stop engages a card and the transparent shield 12 and 10 respectively when the same are supported by easel 6. This form is adapted for use with instrument boards 18 constructed without the bead 20 thereon. The lug 22 in this instance is likewise formed from wall 14 and when removed therefrom leaves opening 52. The function of the clamping means in which is incorporated a lug structure of this character is not altered in any way and while the modified form is structurally different, the primary objects of the invention are all fulfilled by structure embodied therein.

Having thus described the invention, what is claimed as new and desired to be secured by Letters Patent is:

- 35 1. As a new article of manufacture, a card holder comprising an easel, an integral extension therefrom rebent rearwardly thereof to form a supporting bracket in parallelism to said easel and adjustable clamping means carried by the bracket disposed to engage a support behind said easel.
- 40 2. As a new article of manufacture, a card holder comprising an easel, an integral extension therefrom rebent rearwardly thereof to form a supporting bracket, a card stop formed at the juncture of said easel and supporting bracket and adjustable clamping means carried by the bracket behind said easel.
- 45 3. As a new article of manufacture, a card holder comprising an easel, an integral extension therefrom rebent rearwardly thereof to form a supporting bracket, an adjustable clamping means carried by the bracket behind said easel and a stop formed at the juncture of said easel and clamping means comprising a bead against which a card in the easel rests by gravity.
- 50 4. As a new article of manufacture, a card holder comprising an easel, an integral extension therefrom rebent rearwardly thereof to form a supporting bracket, an adjustable clamping means carried by the bracket behind said easel and a convexo-concave stop formed at the juncture of said easel and

clamping means extending forwardly of the major plane of the easel whereby to support a card therein and permit a portion of a support to project beneath said easel.

5. A card holder comprising an easel, an integral extension therefrom rolled to form a convexo-concave bead at the line of juncture with the easel and rebent rearwardly thereof in spaced relation thereto, inturned flanges along each side of said easel to hold, with said bead, a card in position thereon and adjustable clamping means carried by the rebent portion of the easel. 70

6. A card holder comprising an easel, an integral extension therefrom rolled to form a convexo-concave bead at the line of juncture with the easel and rebent rearwardly thereof in spaced relation thereto, and adjustable clamping means carried by the rebent portion of the easel including a lug integral with the wall of said rebent portion, a nut between the lug and rebent portion wall and a threaded bolt passing through the nut. 75

7. A card holder comprising an easel, an integral extension therefrom rolled to form a convexo-concave bead at the line of juncture with the easel and rebent rearwardly thereof in spaced relation thereto, and adjustable clamping means carried by the rebent portion of the easel including a lug integral with the rebent portion wall, a nut between the lug and wall, a hole in lug and rebent portion wall respectively, and a bolt passing through said holes and nut whereby bolt may be turned as the nut is held in position against turning. 85

8. A card holder comprising an easel, an integral extension therefrom rebent rearwardly thereof in spaced relation thereto to form a bracket, and an adjustable clamping means carried by the bracket behind the easel including a lug integral with the bracket wall, a nut between the lug and bracket, whereby to preclude turning of the nut, and a bolt passing through said nut for longitudinal movement toward and from the said easel. 100

In testimony whereof, I hereunto affix my signature.
